AU 291

EX

OR D 13,906

Design No. 13,906, dated May 15, 1883.

UNITED STATES PATENT OFFICE.

HENRY R. VAN EPS, OF PEORIA, ILLINOIS.

DESIGN FOR A FLOWER-STAND.

SPECIFICATION forming part of Design No. 13,906, dated May 15, 1883.

Application filed February 26, 1883. Term of patent 14 years.

To all whom it may concern:

Be it known that I, HENRY R. VAN EPS, a citizen of the United States, residing at Peoria, in the county of Peoria and State of Illinois, 5 have invented and produced a new and original Design for Flower-Stands, of which the following is a specification, reference being had to the accompanying drawings, forming part thereof, and showing a front perspective view 10 of the same in Figure 1, and in Fig. 2 a similar view of the stand with one shelf removed.

The leading feature of my design consists in two or more steps or shelves rising one above the other, each being smaller than the one below, and in an arch spanning the smallest step, 15 and having upon its sides two or more pairs of pockets or small brackets. My whole flower-stand is constructed of finer or larger wire bent into the configurations shown, to serve 20 the different objects of supports, braces, floors, sides, and ornamentation.

In the drawings, S S' S² are the steps or shelves, made rectangular in outline, the lower one, S², of which is shown in Fig. 1, but not in 25 Fig. 2. From the ends of the upper shelf, S, the straight sides B B rise until they meet the top portion, A, of the arch, made semicircular in form. The ends of said semicircular arch 30 A, instead of terminating with the upper extremities of the said sides B B, are bent out horizontally and then back to said sides B B,

to form side pockets C for the reception of flower-pots. About midway between said pockets C and the upper shelf, S, are formed the side pockets D D D D, secured to the 35 sides B B. To the extremity of each of the pockets C C is secured a hook, E, upon which to depend a bird-cage or hanging basket. At the center of the arch A is another hook, E', and a hanging basket (shown in Fig. 1) suspended therefrom. 40

I claim—

1. The design for a flower-stand herein shown and described, the same consisting of the steps or shelves S S' S², having rising from the upper of said shelves an arch consisting of vertical sides B B and semicircular top A. 45

2. The design for a flower-stand herein shown and described, the same consisting of the steps or shelves S S', from the upper one of which 50 rises an arch formed with straight sides B B and semicircular top A, the ends of which are bent into the side pockets C C.

3. In a design for a flower-stand or trellis, the vertical sides B B, having pockets D D D 55 D, and the curved top A, the ends of which are bent to form side pockets, C C.

HENRY R. VAN EPS.
